LOW-LOSS CIRCUIT APPARATUS

Harry Tunick, Rye, N. Y., assignor to Radio Corporation of America, a corporation of Delaware

Original application June 15, 1935, Serial No. 26,749. Divided and this application March 4, 1937, Serial No. 129,008

9 Claims. (Cl. 250—36)

This application is a division of my copending application Serial No. 26,749, filed June 15, 1935, entitled Low loss circuits.

My present invention relates to improved low loss circuit apparatus. It has as its main object the provision of an improved arrangement of a vacuum tube or vacuum tubes and their associated low loss circuits for efficiently producing and/or otherwise dealing with waves of very short wave lengths.

Figures 1 and 2, which correspond to Figures 9 and 10 of my copending application, illustrate preferred forms of my present invention, wherein in one or more vacuum tubes are mounted within concentric resonant low loss circuits.

In the single vacuum tube arrangement of Figure 1, the vacuum tube 900 is mounted within the quarter wave length cylinder 902, as shown. The cylinder 902 is grounded at its bottom end and the grid 904 of the vacuum tube 900 is connected to the outer surface of cylinder 902, as shown. The pair of cylinders 902 and 930 both form one tuned circuit. The plate circuit of the vacuum tube, which consists of a coil 906 and condenser combination 908, is provided with a tuning knob 908 which protrudes through the cover, not shown, of the oven 912. The oven is provided with a thermostat 914, a heater 916 and a battery 918 for rough temperature control.

Fine temperature control is provided within the inner cylinder 902 by means of battery or other source of potential 920, heating resistor 922 and thermostat 924. Output energy is taken from the coil 926 and fed to any suitable load circuit, such as an antenna, 928. The outer concentric cylinder 930 may be omitted, in which case the entire oven 912 should be made of metal or should be provided with metal walls facing the low loss circuit forming the grid circuit of the oscillation generator.

The push-pull arrangement of the system of Figure 1 is shown in Figure 2. The oven 1000 is provided with the heaters 1002, 1004, 1006, 1008 energized by a source of potential 1010, under control of the thermostat 1012. The vacuum tubes 1014 and 1016 are supported on the insulating supports 1018, 1020 and are provided with a common plate or output circuit 1022. The power supply leads 1024 are brought in at the electrical center of the frequency controlling tube 1026, as is also the plate condenser shaft and knob 1027. The inner cylindrical tube 1026 is supported upon the outer concentric cylinder 1028 by means of the insulators 1030. The outer

concentric cylinder, in turn, is supported within the oven 1000 by means of insulators 1032, 1034. The filaments of the vacuum tubes, as shown, are provided with chokes 1040, 1042 which permit the filaments to assume proper high frequency potentials. The grids of the vacuum tubes are tapped to the outer surface of the frequency controlling cylinder 1026 at suitable tapping points 1050, 1052 through the blocking condensers 1054, 1056. Grid bias is obtained through chokes 1058, 1060 and plate potential is obtained through chokes 1062 and 1064, which may be shunted by resistors 1066, 1068, if desired.

It should be understood that the term "ground" used in this specification is not limited to actual earth, but includes any point or surface of relatively fixed alternating current potential.

Having thus described my invention, what I claim is:

1. The combination with a tuned circuit in the form of a concentric line having an outer conductor and a coaxial hollow inner conductor, of a multi-electrode electron discharge device located within said inner conductor, a connection from one electrode of said device to the outer surface of said inner conductor, and a connection from another electrode of said device to another point on one of said conductors of said line.

2. The combination with a tuned circuit in the form of a concentric line having an outer conductor and a coaxial hollow inner conductor connected together at one of their adjacent ends, of an electron discharge device within said inner conductor, said device having a cathode and a grid, a connection from said grid to a point on the outer surface of said inner conductor, and a connection from said cathode to the inner surface of said inner conductor.

3. The combination with a tuned circuit in the form of a concentric line having an outer conductor and a coaxial hollow inner conductor connected together at one of their adjacent ends, of an electron discharge device within said inner conductor, said device having a cathode, a grid, and an anode, a connection from said grid to a point on the outer surface of said inner conductor, a connection from said cathode to one of said conductors, and a tuned circuit of lumped reactance also located within said inner conductor and connected between said anode and a source of polarizing potential.

4. The combination with a tuned circuit com-

prising both a hollow conductor devoid of concentrated reactance and a surrounding outer hollow conducting shell coupled to said hollow conductor to form therewith a high frequency circuit, and having a connection from said outer shell to a point of relatively fixed alternating current potential, of a multi-electrode vacuum tube device having input electrodes and being located within said hollow conductor, said input electrodes being connected to said tuned circuit.

5. The combination with a tuned circuit in the form of a concentric line having an outer conductor and a coaxial hollow inner conductor, of a pair of push-pull connected electron discharge devices located within the interior of said inner conductor, each of said devices having a cathode, an anode, and a grid, connections from said grids to different points on the outer surface of said inner conductor, a connection between said anodes including a tuned circuit of concentrated reactances also located within said inner conductor, means located externally of said concentric line for heating said cathodes and for supplying polarizing potentials to said anodes, and a utilization circuit coupled to said last tuned circuit.

6. The combination with a tuned circuit in the form of a concentric line having an outer conductor and a coaxial hollow inner conductor, of a pair of push-pull connected electron discharge devices located within the interior of said inner conductor, each of said devices having a cathode, an anode, and a grid, connections from said grids to different points on the outer surface of said inner conductor symmetrically disposed with respect to the center thereof, a connection between said anodes including a tuned circuit of concentrated reactances also located within said inner conductor, means located externally of said concentric line for heating said

cathodes and for supplying polarizing potentials to said anodes, and a utilization circuit coupled to said last tuned circuit.

7. The combination with a tuned circuit in the form of a concentric line having an outer conductor and a coaxial hollow inner conductor, of a pair of push-pull connected electron discharge devices located within the interior of said inner conductor, each of said devices having a cathode, an anode, and a grid, connections from said grids to different points on the outer surface of said inner conductor symmetrically disposed with respect to the center thereof, a connection between said anodes including a tuned circuit of concentrated reactances, means located externally of said concentric line for heating said cathodes and for supplying polarizing potentials to said anodes, and a utilization circuit coupled to said last tuned circuit.

8. The combination with a tuned circuit comprising both a hollow conductor devoid of concentrated reactance and a surrounding outer hollow conducting shell, of a pair of multi-electrode vacuum tubes located within said hollow conductor, each of said devices having a grid electrode coupled to the outer surface of said hollow conductor, whereby said tuned circuit constitutes the input circuits for said vacuum tubes.

9. The combination with a tuned circuit comprising both a hollow conductor devoid of concentrated reactance and a surrounding outer hollow conducting shell, and having a connection from said outer shell to a point of relatively fixed alternating current potential, of a multi-electrode vacuum tube located within said hollow conductor and having certain of its electrodes connected to said tuned circuit, whereby said tuned circuit constitutes the input circuit for said vacuum tube.

HARRY TUNICK.
